Filed Nov. 2, 1971, Ser. No. 195,066

Term of patent 14 years

Int. Cl. D7—05

U.S. Cl. D49—29

FIG. 1 is a side elevation of the mop wringer showing our new design;

FIG. 2 is a similar view at right angles thereto;

FIG. 3 is a partial vertical section through the wringer; and

FIG. 4 is a top plan view thereof.

The mop shown in dotted lines in FIG. 3 is disclosed for illustrative purposes only and forms no part of the claimed design.

I claim:

The ornamental design for a mop wringer, substantially as shown and described.
